CLAIM

The ornamental design for a golf chipping game, as shown and described.

DESCRIPTION

FIG. 1 is a top perspective view of a golf chipping game shown in FIG. 1.

FIG. 2 is a top view of the golf chipping game shown in FIG. 1.

FIG. 3 is a bottom view of the golf chipping game shown in FIG. 1.

FIG. 4 is a right-side view of the golf chipping game shown in FIG. 1.

FIG. 5 is a left-side view of the golf chipping game shown in FIG. 1.

FIG. 6 is a rear-side view of the golf chipping game shown in FIG. 1; and,

FIG. 7 is a front-side view of the golf chipping game shown in FIG. 1.

The broken lines in the figures show portions of the golf chipping game that form no part of the claimed design.

1 Claim, 7 Drawing Sheets
